RADIO RECEIVER SYSTEM

Harold H. Beverage, Riverhead, N. Y., assignor to
 Radio Corporation of America, a corporation of
 Delaware

Application October 10, 1942, Serial No. 461,527

11 Claims. (Cl. 250—20)

1

My present invention relates to ultra-high frequency radio receivers, and more particularly to radio receiving systems capable of receiving amplitude modulated carrier energy free of undesired frequency modulation effects.

It is the usual practice at relatively low radio frequencies to stabilize the transmitter, and to place radio frequency selectivity ahead of a superheterodyne receiver first detector thereby to improve the signal to noise ratio at the first detector. At very high radio frequencies, however, this is impractical at present, because of the lack of devices that will amplify satisfactorily at these frequencies. This makes it impracticable to stabilize the frequency of the transmitter, or to build a radio frequency amplifier ahead of the first converter. Accordingly, in the prior art when radio transmission has been practiced in the extremely high radio frequency range, it has been necessary to allow the transmitter to vary over a comparatively wide band of frequencies. Consequently, the signal selector circuits of the associated superheterodyne receiver were designed so that the acceptance bands thereof were wide enough to accept the signaling modulations plus the frequency variations of the transmitter and the receiver local oscillator. This results in a relatively poor signal to noise ratio at the receiver output.

It may, therefore, be stated that it is one of the main objects of my present invention to provide communication at ultra-high radio frequencies and to use a narrow intermediate frequency pass band which is only wide enough to select the necessary modulation frequencies; the noise being greatly reduced due to the narrow intermediate frequency (I. F.) band since the noise is a function of the band width.

Another important object of my invention may be stated to reside in the provision of a system of receiving amplitude modulated signals without the usual difficulties caused by coincidental undesired frequency modulation (F. M.).

Another important object of this invention is to make possible the use of a superheterodyne receiver in which the band width of the I. F. network does not need to be excessively wide thereby making it possible to obtain freedom from interference and to secure an improved signal to noise ratio.

Another object of my invention is to provide an arrangement for receiving amplitude modulated signals which eliminates the difficulties caused by coincidental undesired frequency modulation, wherein the local beat oscillator has

2

the same frequency variations as the signal with the result that the intermediate frequency energy has no frequency variation.

Yet another object is to provide a receiving system for amplitude modulated signals with coincidental undesired frequency modulation wherein the frequency variations are removed by deriving local heterodyne energy from the signal energy.

Still another object of my invention is to provide a receiving system for amplitude modulated signals which eliminates coincidental undesired frequency modulation at the intermediate frequency by beating the signals with local oscillations derived from the signal energy, and passing said local oscillations through a limiter to remove amplitude variations thereby obtaining linear response.

It is still necessary in the receiving systems disclosed in this application to have the input circuit to the first converter sufficiently wide to allow for the variations of the transmitter. However, the noise at the first detector may be considered as a continuous spectrum of noise which is in effect scanned by the I. F. amplifier in accordance with the frequency variations of the received signal so that at any instant the I. F. network "sees" only a comparatively narrow band of frequencies thereby resulting in an improved signal to noise ratio at the receiver output.

Stated generally, in my receiving system undesired frequency modulation effects of the received signals are completely eliminated at the operating I. F. of the receiver by an arrangement whereby the high frequency oscillations which beat with the received signal to produce the I. F. energy is derived from a combination of high frequency energies. These energies are those of the local oscillator and the incoming signal so that the conventional high frequency oscillator of a heterodyne system is replaced by oscillations having exactly the same frequency variations as the received signal itself. Consequently, the beat derived from the local oscillations and the signal has none of the frequency variations of the original signal, and the I. F. amplifier need be only wide enough to transmit the essential modulation side bands.

The novel features which I believe to be characteristic of my invention are set forth with particularity in the appended claims; the invention itself, however, as to both its organization and method of operation will best be understood by reference to the following description taken in connection with the drawing in which I have indicated diagrammatically several circuit organi-

zations whereby my invention may be carried into effect.

In the drawing:

Figs. 1, 2, 3 and 4 schematically show respectively different embodiments of the invention.

Before describing the circuits in detail, it is pointed out that it has been the practice to stabilize the frequency of the transmitter in radio frequency communication by the use of stable master oscillators. For example, resonant lines and crystal-controlled oscillators have been utilized for frequency stabilization. Generally, this is a desirable solution to the problem since it conserves frequency space, and makes possible the use of a simple receiver. However, at frequencies of the order of thousands of megacycles (mc.) it is frequently very difficult, and in some cases practically impossible, to stabilize the frequency of the transmitter, since a very high degree of frequency multiplication would be required if conventional stabilized oscillators were employed. In other cases, unconventional devices are required to generate these very high frequencies efficiently, and, therefore, conventional methods of frequency stabilization are not applicable.

Referring now, specifically to the schematic radio receiving system shown in Fig. 1, let it be assumed that there has been radiated from an ultra-high frequency transmitter an amplitude modulated carrier wave whose carrier frequency is chosen at 2,000 megacycles. As is well known to those skilled in the art, the signal energy may be radiated from a parabolic antenna, and the radiated signal energy may be received by a parabolic antenna 1. The collected modulated carrier wave energy is concurrently applied to the first converter 2 and auxiliary converter 18 of a super-heterodyne receiving system. A crystal-controlled oscillator 16 is provided, and this oscillator functions to provide stable oscillations at a fundamental frequency of 20 mc. It is not believed necessary to show the circuit details of such a stabilized oscillator, since those skilled in the art will readily be able to construct an oscillator of this type. The 20 mc. oscillations are of substantially constant amplitude, and are applied to frequency multipliers 13, 12 and 11 in succession. These frequency multipliers 13, 12 and 11 respectively multiply their respective input frequencies by factors of 5, 5 and 3. In this way the 20 mc. energy is stepped up in frequency to a value of 1500 mc. The output energy of multiplier 11 at 1500 mc. is applied to the first converter. Hence, there is provided at the output of the first converter 2 intermediate frequency energy of 500 mc.

The 500 mc. I. F. energy output of the converter 2 is modulated, of course, in accordance with the signal modulations which existed on the carrier energy applied to antenna 1. In like manner, the output of crystal-controlled oscillator 16 is multiplied by successive frequency multipliers 13, 14 and 15 to a frequency of 1600 mc. These multipliers have respective multiplication factors of 5, 4 and 4. The latter energy of 1600 mc. is applied to auxiliary converter 18 along with the original amplitude modulated carrier wave energy of 2,000 mc. Hence, there is produced at the output of the auxiliary converter 18 amplitude modulated carrier energy of 400 mc.

As is well known, the heterodyning process does not alter the total frequency change. Accordingly, if the signal energy outputs of converters 2 and 18 are combined, the output signal energies thereof will provide a second I. F. of 100 mc.

Since the frequency variations of the 500 mc. and 400 mc. energies are identical, the second I. F. energy of 100 mc. will not have any of the incidental frequency variations which existed in the original signal.

Prior to impression of the first I. F. energy upon the converter 4, the 500 mc. energy is passed through a band pass filter 3 to remove undesired heterodyne combination frequencies. The 100 mc. energy may be amplified by an I. F. amplifier 5, and the resulting I. F. energy of 100 mc. is then applied to a third converter 6. If desired, the 100 mc. energy can be reduced to 20 mc. by utilizing the output of oscillator 16. In this case, frequency multiplier 17 multiplies the 20 mc. oscillations to the fourth harmonic, and the resulting 80 mc. signal energy is applied to the third converter 6 thereby to provide the third I. F. energy of 20 mc. The latter may be amplified as at 7, and after a fourth conversion at network 8 the resulting modulation signals can be amplified and reproduced.

In order to make the response of the receiving system linear, there is shown a limiter 20 which follows filter network 19. The function of this limiter is to prevent any amplitude variation being applied to the converter 4. Hence, the 400 mc. energy applied to converter 4 has no amplitude variation no matter what the variations of the incoming amplitude modulated carrier energy may be. This is an important advantage of the present invention, because if the limiter were omitted, and if amplitude variations were allowed in both the 400 and 500 mc. energies, it is obvious that the response in converter 4 would not be linear.

In Fig. 2 I have shown an embodiment of the receiving system which requires less equipment. Instead of using the crystal-controlled oscillator 16, frequency multiplier 17 and the frequency multipliers 11 to 15, there is employed an oscillator 40 which provides oscillations of constant amplitude at 1550 mc. These oscillations are fed to a modulator 39 along with constant amplitude oscillations from the 50 mc. oscillator 38. The modulator 39 is so constructed that the carrier frequency of 1550 mc. is suppressed, while the sidebands of 1550 plus or minus 50 mc. are passed. Filters 33 and 34 respectively pass the resulting 1500 mc. sideband or the 1600 mc. sideband. The filter 33 feeds the 1500 mc. energy to the first converter 2, while the filter 34 feeds the 1600 mc. energy to the auxiliary converter 18. The outputs of converters 2 and 18 are treated as shown in Fig. 1. The third converter 6 is fed with the 100 mc. energy, and is suitably supplied with 80 mc. oscillations (as from networks similar to 16, 17 of Fig. 1) in order to reduce the 100 mc. energy to the 20 mc. value.

Those skilled in the art are fully aware of the manner of constructing frequency multipliers of the type shown in Fig. 1. Furthermore, the limiter 20 may be of any desired type, such as, for example, a readily-saturatable amplifier. The modulator circuit 39 of Fig. 2 is well known to those skilled in the art.

The system of Fig. 1 may be further simplified as shown in Fig. 3. In this case, a suppressed carrier modulator 55, similar to the modulator 39 of Fig. 2, is fed with energy at 1550 mc. from oscillator 56. Oscillator 57 provides modulator 55 with the 50 mc. energy. The resulting output of modulator 55 contains frequencies of 1500 mc. and 1600 mc. These two frequencies beat with the collected 2000 mc. energy in the first con-

verter 2. The output of converter 2 will, therefore, contain both 500 mc. beat energy and 400 mc. beat energy. The filters 47 and 48 respectively select the 500 mc. beat energy and the 400 mc. beat energy. The 400 mc. signal energy is passed through an amplitude modulation limiter 49. The limited 400 mc. signal energy and the 500 mc. signal energy are applied to the second converter 4. The resulting 100 mc. signal energy is then treated by the successive stages 5, 6, 7 and 8 as shown in Fig. 1. In the system of Fig. 3, the networks 11 to 15, 18, 19 and 20 of Fig. 1 are omitted. The third converter 6, fed with amplified 100 mc. energy from amplifier 5, has applied thereto the 80 mc. oscillations from multiplier 17 thereby to reduce the frequency of the 100 mc. energy to the lower frequency value as shown in Fig. 1. The oscillator 16 supplies 20 mc. oscillations to multiplier 17, as in Fig. 1.

In Fig. 4 there is shown another modification in which there is employed a relatively high frequency oscillator 17. This oscillator 17 is followed by a minimum number of frequency multipliers 76, 75 and 74. The output of the multiplier 74 is the twelfth harmonic of oscillator 17. The twelfth harmonic energy is heterodyned with the received modulated 2000 mc. energy at the first converter 2. The resulting 800 mc. I. F. energy is combined with the 100 mc. oscillations from oscillator 17 at a second converter 61 to produce a modulated beat output of 700 mc.

The 200 mc. output energy of multiplier 76 is combined with the 800 mc. I. F. energy at the third converter 68 to produce a modulated carrier output of 600 mc. The 700 mc. energy is passed through a filter 69, and the filtered energy is then applied to a fourth converter 70. The 600 mc. energy output of third converter 68 is filtered as at 71. The filtered energy is then subjected to amplitude limitation at 79, and the output of the limiter 79 is applied to the fourth converter 70. The beat output energy of the fourth converter 70 is the signal modulated carrier energy reduced to a carrier frequency of 100 mc. The latter energy may then be subjected to further conversion for the production of the modulated signals as shown in Fig. 1. That is to say, the fifth converter is fed with 80 mc. oscillations from a source of oscillations such as is exemplified by oscillator 16 and multiplier 17 of Fig. 1. The resulting 20 mc. output of the fifth converter is then amplified, and further converted as shown at networks 7 and 8 of Fig. 1.

While I have indicated and described several systems for carrying my invention into effect, it will be apparent to one skilled in the art that my invention is by no means limited to the particular organizations shown and described, but that many modifications may be made without departing from the scope of my invention.

What I claim is:

1. A method of signalling at high frequency with amplitude modulated carrier waves having incidental frequency modulation effects which includes providing stable local oscillations of constant amplitude and of a relatively lower frequency than the carrier frequency of said modulated carrier waves, frequency multiplying the local oscillations to a frequency differing from the carrier frequency by a predetermined value, heterodyning the modulated carrier waves and multiplied oscillations to produce a beat frequency, frequency multiplying said local oscillations to a second frequency different from the

first multiplied value, combining the modulated carrier waves and the second multiplied oscillations to provide a second beat frequency different from the first beat frequency, amplitude limiting the current of one of said beat frequencies to remove amplitude variations therefrom, and after said limiting combining the two beat frequencies to provide a third beat frequency substantially free of said modulation.

2. A method of signalling at high frequency with amplitude modulated carrier waves having incidental frequency modulation which includes providing frequency-stable local oscillations of constant amplitude and of a relatively lower frequency than said carrier, frequency multiplying the local oscillations to a frequency differing from the carrier frequency by a predetermined value, heterodyning the modulated carrier waves and multiplied oscillations to produce a beat frequency having said incidental frequency modulation, frequency multiplying said local oscillations to a second frequency different from the first multiplied value, combining the modulated carrier waves and the second multiplied oscillations to provide a second beat frequency different from the first beat frequency but having said incidental frequency modulation, amplitude limiting the second beat energy to remove amplitude variation thereof, and combining after said limiting the two beat frequencies to provide a third beat frequency substantially free of said incidental frequency modulation.

3. A method of signalling at high frequency with amplitude modulated carrier waves having incidental frequency modulation which includes providing frequency-stable local oscillations of constant amplitude and of a relatively lower frequency than the carrier frequency of said modulated carrier waves, frequency multiplying the local oscillations to a frequency differing from the carrier frequency by a predetermined value, heterodyning the modulated carrier waves and multiplied oscillations to produce a beat frequency having said incidental frequency modulation, frequency multiplying said local oscillations to a second frequency different from the first multiplied value, combining the modulated carrier waves and the second multiplied oscillations to provide a second beat frequency different from the first beat frequency but having said incidental frequency modulation, subjecting one of the beat frequency currents to amplitude limiting, combining the two beat frequencies after said limiting to provide a third beat frequency substantially free of said incidental frequency modulation, reducing the third beat energy to a lower frequency value, and demodulating the reduced frequency energy.

4. A method of signalling at ultra-high frequency with amplitude modulated carrier waves which have incidental frequency modulation, which includes providing frequency-stable local oscillations of constant amplitude and of a relatively lower frequency than the carrier frequency of said modulated carrier waves, changing the local oscillations to a frequency differing from the carrier frequency by a predetermined value, heterodyning the modulated carrier waves and changed oscillations to produce a beat frequency having said incidental modulation, changing said local oscillations to a second frequency different from the first value, combining the modulated carrier waves and the second oscillations to provide a second beat frequency different from the first beat frequency but having like incidental

frequency modulation, eliminating amplitude variations in the current of the second beat frequency, and combining after said elimination the two beat frequencies in such relation as to provide a third beat frequency free of said incidental modulation.

5. A method of signalling at high frequency with amplitude modulated carrier waves which includes providing local oscillations, frequency multiplying the local oscillations to a frequency differing from the carrier frequency by a pre-determined value, heterodyning the carrier waves and multiplied oscillations to produce a beat frequency, frequency multiplying said local oscillations to a second frequency different from the first multiplied value, combining the carrier waves and the second multiplied oscillations to provide a second beat frequency different from the first beat frequency, amplitude limiting the energy of the second beat energy to remove all amplitude variation thereof, and combining the two beat frequencies in such relation as to provide a third beat frequency which is solely amplitude modulated.

6. A method of receiving amplitude modulated ultra-high frequency carrier wave energy which has incidental undesired frequency modulation consisting in reducing the carrier frequency of the received wave energy to a lower carrier frequency, deriving from the received wave energy local oscillations whose frequency is substantially different from said lower carrier frequency but which oscillations have the same undesired frequency modulation as said received wave energy, completely removing amplitude variations from said local oscillations, and heterodyning the lower carrier frequency energy with said local oscillations after said amplitude variation removal to produce intermediate frequency energy having said amplitude modulation but being free of said incidental frequency modulation.

7. A method of receiving amplitude modulated carrier wave energy which has undesired incidental frequency modulation which includes the steps of deriving local oscillations from the received carrier wave energy which have a frequency different from the carrier frequency of the wave energy, removing all amplitude variations from the local oscillations, beating the received carrier energy with said local oscillations derived from the received carrier wave energy after said amplitude variation removal, and demodulating the resulting amplitude modulated intermediate frequency energy which is free of said incidental frequency modulation.

8. A method of eliminating undesired frequency modulation from received amplitude modulated carrier wave energy which includes the steps of deriving local oscillation energy subject to said undesired modulation from the received carrier energy, combining the received energy with the

local oscillation energy in such relation as to eliminate said undesired frequency modulation, and subjecting the local oscillation energy to amplitude limiting prior to said combining step thereby to remove amplitude variations in the local oscillation energy and to obtain linear response.

5 9. In an ultra-high frequency receiver, the method comprising the steps of heterodyning received amplitude modulated ultra-high frequency carrier waves with separate local oscillations of different frequency to provide separate amplitude modulated intermediate frequency energies of different frequency but of like incidental frequency variation, amplitude limiting one of the intermediate frequency energies to remove amplitude variation thereof, beating the two intermediate frequency energies together to provide a third beat energy free of incidental frequency variation, and demodulating the beat energy.

10 20 10. In an ultra-high frequency receiver, the method comprising the steps of heterodyning received amplitude modulated ultra-high frequency carrier waves subject to undesired incidental frequency deviation with a pair of separate local oscillations of different frequency to provide separate amplitude modulated intermediate frequency energies of different frequency but subject to said incidental deviation in like manner, limiting one of the intermediate frequency energies to remove amplitude variation, beating the limited intermediate frequency energy together with the other intermediate energy to provide a third beat energy free of said deviation, and demodulating the beat energy.

25 30 35 11. A method of receiving ultra-high frequency carrier energy which is modulated in two different types of modulation, one type being desired and the other undesired, which includes the steps of converting the received energy into at least two modulated carrier energies of different frequencies and modulated in the same manner as the received energy, removing from one of the two converted energies all variation representative of the desired type of modulation, and heterodyning the two carrier energies of different frequencies thereby to provide a resulting modulated beat energy which is free of the undesired type of modulation.
